UNITED STATES PATENT OFFICE.

DAVID M. REID, OF HAMILTON, ONTARIO, CANADA.

ANCHOR.

1,264,682.

Specification of Letters Patent.

Patented Apr. 30, 1918.

Application filed October 9, 1916. Serial No. 124,641.

To all whom it may concern:

Be it known that I, DAVID M. REID, a subject of the King of Great Britain, residing at Hamilton, in the Province of Ontario and 5 Dominion of Canada, have invented certain new and useful Improvements in Anchors, of which the following is a specification.

This invention relates to anchors, and is designed to be used as land and boat anchors, and has for its principal object to provide means whereby the arms or flukes of the anchor may, when not in use be folded against the shank of the anchor, and thus enable the same to be packed or stored away 15 in a relatively small space, and when in use said arms or flukes will open out automatically to their fullest and serve to form a secure holding means for whatever may be connected to the shank.

20 Another object of the invention is to provide an anchor of this type made wholly of rolled metal cut to size and bent into the required shape, which operations may be quickly, readily, and economically performed, and while having the maximum 25 degree of holding power, may be produced at the minimum of expense.

A further object of the invention is to provide an anchor of the class described 30 having folding arms or flukes, and which is so made and combined that it will have a plurality of arms pivoted to a shank which, when in use, stands at various angles with relation to the axis of said shank, and when 35 not in use, these arms or flukes can be folded to lie so closely against the shank that the anchor may, when employed as a boat anchor, be passed into and out through the hawse pipe, stood on end, or disposed in a 40 flat position when stored away so as to occupy the least possible space and yet be in convenient position for quick use when desired.

With these as the principal objects in 45 view the invention consists of the novel construction, combination and arrangement of parts as hereinafter described, pointed out in the appended claim and illustrated in the accompanying drawing, in which,

50 Figure 1 is an elevation of the improved anchor in its simplest form;

Fig. 2 is a sectional view through one of the arms or flukes thereof on the line 2—2;

Fig. 3 is an elevation of the anchor as de-

signed more particularly for boat use, but 55 which may be used as a land anchor;

Fig. 4 is a detail perspective view of the lower end of the shank of the anchor.

In the drawings 10 is the shank of the anchor which, as shown in Fig. 3, consists 60 of a length of rolled metal, the upper end 11 and the lower end 12 being twisted or turned at right angles to the central portion 13. To the upper end 11 the bracing wire or cable, not shown, is attached, while to the 65 lower portion 12 there is pivoted a pair of oppositely-extending arms or flukes 14, similar arms or flukes 15 being pivotally mounted upon the central portion 13 of the shank 10. The arms or flukes 15, as shown, project substantially at right angles to the direction in which the similar arms or flukes 14 extend and all of said arms when not in 70 use fold upwardly against the shank. The arms 15 lie against the opposite flat sides 75 of the central section 13 of the shank and through perforations in their inner ends to a perforation in the shank is passed a pivot bolt or rivet 16 which is maintained in place by a nut screwed on the ends of the bolt. 80 Each arm or fluke 15 is made of rolled metal, the inner half of which lies flatwise with and parallel to the flat sides of the section 13; the outer half 17, however, of each arm is at right angles to the inner half, the 85 arm, as will be seen, being given a twist or quarter turn and the outer end tapered and formed into a point 18. Projecting outwardly from the shank on each side a short distance below the pivot 16 is a stud or stop 90 19 upon which the arms 15 bear when they are open as indicated in the drawing, and which hold said arms at such an angle as will give a firm grip in the ground or on the bottom of a river, lake or other body of 95 water when used as a boat anchor. By giving the outer ends of the arms or flukes the turn described, they present their flat broad sides to the ground and thus more effectually hold the anchor than would be the case 100 if the edge of the flukes engaged the earth.

The arms or flukes 14 are duplicates of the arms 15 and need no further description other than to say that instead of the stops 19 the lower end of the shank 12 is centrally 105 divided longitudinally and the divided ends turned in opposite directions as at 20 and then upwardly as at 21 forming thereby a

shouldered stop on each side of the shank into which the respective arms or flukes 14 enter and are supported in their working positions.

5 An anchor such as described may be used for land and boat purposes, but for most purposes when the anchor is to be used on land for anchoring telephone, telegraph and other poles, fence and like posts and other 10 articles requiring anchorage by means of guys, anchors such as shown in Fig. 1 having two flukes or arms only are preferred. In this form of the device, the shank 10^a is short and without the twist or right angle 15 bends therein, but has in its upper end an opening to which is attached the guy wire or cable, and against which the arms or flukes 14 are folded when about to be put into use or to be stored away. These arms 20 like those of the larger type of anchor have an intermediate twist or right-angle turn to cause the flattened faces of the outer ends of the arms to bear against the earth when strain is applied to the anchor and thus afford a more rigid and a securer anchorage. 25

When used as a pole or post anchor a hole is bored in the ground by means of a bar or rod of suitable kind and to the desired depth and the anchor illustrated in 30 Fig. 1 folded with the arms or flukes 14^a parallel with the shank 10^a and a cable or wire attached to the shank is lowered into the hole until it reaches the bottom which is sufficiently deep to insure the points 18 of 35 the arms being some distance below the surface of the ground. The arms being then pushed outwardly as far as the hole will permit tension is placed upon the wire or cable, and by such tension the shank 10 is drawn 40 outwardly toward the top of the hole a greater or less distance.

The points 18 of the arms being pressed against the ground are forced sidewise into the earth penetrating the same with more or less degree of readiness as the tension is increased or decreased until the arms stand substantially at right angles to the shank, 45 as shown in Fig. 1. In this position these arms are firmly secured in the earth and will stand far greater strain than they are liable to be subjected to in use and will by their 50

secure holding properties maintain the pole or post in its upright position under most severe strains.

When used as a boat anchor, this device 55 when thrown overboard naturally assumes the position with its arms or flukes outstanding as shown in Fig. 3, the weight of said arms causing them to open out. Upon reaching the bottom of the river, lake or 60 other body of water, the shank 10 will lie in a horizontal position with two of the arms or flukes upon the bottom which, as the anchor is dragged along by the moving boat, will enter the sand or mud on the 65 bottom and bring the boat to a stop. Should the anchor be rotated or turned over while being dragged along the bottom before securing a hold therein, the position of the flukes is such that two of them will always 70 be in position to engage the bottom. When the anchor is raised, it is withdrawn from the bottom in the same manner as the ordinary anchor, the cable being pulled in until the shank 10 stands practically in a vertical 75 direction as in Fig. 3, thus raising the arms from the bottom and permitting the anchor to be readily drawn upwardly when it is taken aboard as usual and being of a folding type is easily stored away.

What is claimed is:

An anchor having a shank formed of a flat bar of metal, a portion of said bar near its lower end being bent on the longitudinal axis of the shank at a right angle to the remainder of the bar, the lower end of said bar being in the same plane as the upper portion, said lower portion having a blunt end centrally split and bent to form two oppositely turned hooks opening upwardly, 85 and a pair of arms or flukes pivoted to the shank above the hooks and adapted to be folded against the shank when not in use or to be extended outwardly at an angle to the shank and supported in such position 90 by said hooks.

In testimony whereof I affix my signature in presence of two witnesses.

DAVID M. REID.
